Filed Aug. 21, 1973, Ser. No. 390,300

Term of patent 14 years

Int. Cl. D7—99; D26—01

U.S. Cl. D7—2

The figure is a perspective view of a combined revolving condiment server and candle holder or the like showing my new design.

A perspective view from the opposite aspect would be substantially the same as shown in the figure. The bottom is plain and unornamented.

I claim:

The ornamental design for a combined revolving condiment server and candle holder or the like, as shown and described.
